VARIABLE LINER GAUGE FOR INTEGRAL
LINE-CASTING TYPE MACHINES

Charles A. Spickler, Yardley, Pa.

Application March 26, 1935, Serial No. 13,099

3 Claims. (Cl. 29—84)

This invention relates to devices for use in setting a liner tip in the mold slot of an integral line-casting type machine and particularly to simple and inexpensive means adapted for this purpose when the mold slot is of any desired width for forming any desired size of type body.

On integral line type-casting machines the length and size of type lines are regulated by interchangeable steel blocks called liners.

10 A so-called "poor man's liner" has been in common use in printing plants for years as an emergency substitute and also for economy's sake.

Such liners are formed by positioning a steel member such as a "30-pica liner" in the mold slot adjacent one end thereof, placing a steel liner tip in the mold slot at the proper distance from the opposite end thereof and bonding the 30-pica liner and liner tip together with type metal 20 by the first casting operation.

Because of the contraction of type metal in commercial use (theory to the contrary), and because of warpage of the mold cap, it is a lucky 25 fea to set the steel tip in the mold slot with hope of any degree of accuracy in the final product using the crude means at the disposal of a linotype operator.

It is with the problem of warpage and of shrinkage that this invention has to deal in setting a liner tip. In the event of a warped mold cap, the cap, warped in a slight upward bow with its ends resting on a constant liner and a 30-pica liner of the same body, will not clamp 30 a liner tip of the same body and hold it firmly 35 for the first binding cast of the machine.

The alternative which the invention proposes to provide for the purpose of overcoming these difficulties is to use a tip and a constant liner of the type body desired and a 30-pica liner of less thickness, permitting the mold cap to rest on and hold the tip firmly, which will produce the desired type line. There is no demand for accuracy in the type metal used as a binder for the tip, for its sole usefulness is as a binder 40 and it is thrown aside when a new setting of the tip is desired.

Among the principal objects of the present invention are to provide methods and means for accurately setting the liner tip in the mold slot in any desired position; to provide simple and inexpensive means adapted for use in setting the liner tip, and to overcome the difficulties presented by warping of the mold cap and shrinkage of the type metal.

The accompanying drawing shows the essential features of the invention and their relation to the old structure and connection therewith:

Fig. 1. Plan of a typical embodiment of the invention, showing the scale set for line of type 5 9 picas long.

Fig. 2. Elevation of the form of the invention illustrated in Fig. 1.

Fig. 3. Elevation of mold-cap 2, constant liner 3, 30-pica liner 4, and mold base 11.

Fig. 4. Plan of mold, constant liner 3, tip 5, and the invention placed in the 30-pica liner slot 6, (Fig. 3).

Fig. 5. Elevation of "poor man's liner", a fabrication composed of the 30-pica liner 4, 15 binding metal 12, liner tip 5.

A detailed explanation follows:

With the invention used as a guide it is possible to set a liner tip of the smallest and tips for all larger size type bodies, for its greatest 20 thickness is less than the thickness of the smallest commonly used type body.

To set a 5½-point tip to produce the product of an all-steel liner 9 ems long, move the scale in its holder until the 9 scribe registers with the 25 scribe on the beveled window ledge of the holder 8, as shown in Fig. 1.

The lug 9, Fig. 2, is inserted in the liner recess 6, Fig. 3, with the projections 7 of the holder on either side of the liner stop and adjacent the recess 6. The 5½-point liner tip 5, Fig. 4, is then inserted in the mold slot, using the square edge formed by the projecting L-shaped portion at the end of the scale as a guide.

The mold-cap 2 is clamped in place, the invention removed and a 5-point 3-pica liner is inserted in its place at 6 and "jacked up" to the mold-cap, shutting off the approximate .085 inch space above the 5-point 30-pica liner with a sliver of type metal picked from the floor, and typesetting can proceed. The method, with graduated 40 uniformity, is to be used for larger sized type bodies.

I claim:

1. A device for setting a liner tip in the mold slot of an integral line-casting type machine comprising a member formed with means thereon for engaging a recess in the mold slot to hold said member in fixed position with respect thereto and an element movable with respect to said member and graduated to indicate the relative positions thereof, said element having a portion formed to engage a liner tip to position the same.

2. A device for setting a liner tip in the mold slot of an integral line-casting type machine comprising a member formed with means thereon for engaging a recess in the mold slot to hold said member in fixed position with respect thereto and an element slidably mounted on said member and graduated to indicate the position thereof, said element having a portion thereof formed to engage a liner tip to position the same.

3. A device for setting a liner tip in the mold slot of an integral line-casting type machine comprising a member formed with means thereon for engaging a recess in the mold slot to hold said member in fixed position with respect thereto and an element slidably mounted on said member and graduated to indicate the position thereof, said element having a squared end for engaging the liner tip to position the same. 5

CHARLES A. SPICKLER. 10
